SUPPORTING AND LOCKING STRUCTURE
FOR COLLAPSIBLE WALL SHELVES

Frank W. Krueger, Saratoga, Calif., assignor, by
mesne assignments, to Rheem Manufacturing
Co., Richmond, Calif., a corporation of Cali-
fornia

Application August 6, 1949, Serial No. 108,922

4 Claims. (Cl. 311—19)

1

This invention relates to shelf structures, and more particularly to novel support, locking and release means for collapsible shelf structures for stoves and the like.

Among the objects of the invention are the following: To provide a novel and efficiently operable operating mechanism for collapsible shelves; to provide a collapsible shelf structure having simple support mechanism comprising lever means operable in the absence of spring elements, or the like, to releasably support and lock a shelf in a horizontal raised position; to provide such shelf support mechanism with trigger means integral with the lever means operable to release said lever means from their position of support of the shelf to allow the lowering or collapsing of the shelf to a vertical or inoperative position; and to provide an operating mechanism for a collapsible shelf so arranged as to be accessible at the upper side of the supported shelf for manual operation to return the shelf to a vertical or collapsed position.

In summary, the shelf support mechanism of the invention comprises first class lever means movable with the shelf in sliding engagement with the support member to which the shelf is pivotally connected, said lever means being provided at one end with locking means engageable with said support member and at the other end with trigger means integral therewith and adapted upon the application of manual pressure thereto to release said lever means from locking engagement with the support member. Said lever means is further characterized by such conformation and such disposition of its pivotal connections with the shelf as to cause an unbalancing of the lever means in such a direction as to gravitationally urge the lever means into locking relation with the support member for the shelf upon the raising of the shelf to a horizontal position for use.

Further objects and advantages of the invention will be apparent from the following description taken in conjunction with the drawings forming a part of this specification, and in which:

Figure 1 is a view in front elevation of the splash-plate of a stove provided with a collapsible shelf embodying the shelf support mechanism of the invention;

Figure 2 is a view in front elevation of the structure of Figure 1, showing the shelf in vertical or collapsed position;

Figure 3 is an enlarged detail view, partly broken away, as taken along the line 3—3 of Figure 1;

2

Figure 4 is an enlarged detail view in section taken along line 4—4 of Figure 1;

Figure 5 is an enlarged view in section taken along line 5—5 of Figure 1;

Figure 6 is a view taken along line 6—6 of Figure 5; and

Figure 7 is an enlarged detail view of the rearward end of a locking lever of the shelf mechanism, showing in solid outline the lever in locked position and, in dotted outline, the lever in a position it might assume, prior to being positively forced to the locking position.

Referring to the drawings, 10 indicates generally a structural support member shown in the form of a backguard or splash-plate member for a stove, said member 10 in such environment being provided with a forward wall 12 and side and top walls 14 and 16 integral therewith. It will be understood that the splash-plate member 10 is supported or secured in conventional fashion adjacent the rearward edge of the burner or grill surface of the stove, not shown. A pair of spaced vertical support members 18 having fixedly secured thereto, as by rivets 20, a pair of angle brackets 22 are carried at the inside surface of the wall 12 of the splash-plate, as by bolts 24 in threaded relation with nuts 26. Molding strip members 28 are secured to the outer face of wall 12 by the bolts and nuts 24 and 26. The members 18 are provided at their upper ends with inwardly offset bosses 30. Links 32 extending through coincident apertures in the angle brackets 22, wall 12 and molding strips 28 are secured to the bosses 30, as by bolts 34 extending through the bosses and into threaded relation with nuts 36. The outer ends of links 32 serve to pivotally support a shelf indicated generally at 38 provided with a skirt portion 40.

The means provided for pivotally connecting the shelf 38 to the links 32 comprise lever sheaths or housing members 42, one at each side of the shelf 38, provided with a pair of inwardly offset bosses 44 serving as the loci of connection between the lever housing members 42 and the shelf 38, said connection being achieved by rivets 46. The outer ends of links 32 are journaled within the inner ends of lever housings 42, as by rivets 48 affording a pivotal connection therebetween.

The members 42 also serve as housing members and reaction members for a portion of the shelf locking means provided, said locking means comprising first-class levers 50 pivotally supported on pins 52 carried by the housing members 42. The levers 50 are provided with ar-

cuately offset rearward portions 54 adapted to travel in apertures 56 and 58 provided, respectively, in the molding members 28 and the front wall 12 of the splash-plate 10. At their forward ends the levers 50 are provided with trigger members 60 extending freely through slots 62 provided in the housing members 42, while at their rearward ends the levers 50 are provided with relatively wide notches 64.

The levers 50 are so arranged with respect to the geometry of their parts and the point of placement of the pivotal connections 52 that when the shelf 38 is in the collapsed or folded position of Figure 2, the unbalance of the levers 50 causes a tendency to clockwise rotation of the levers, using Figure 5 for reference purposes in this connection, to thus maintain the arcuate under-surfaces of portions 54 of the levers in engagement with the lower edges of the lever apertures 56. Thus, as the shelf 38 is manually raised toward the horizontal or extended position of Figure 5, the undersides of the portions 54 of the levers are maintained in travelling engagement with the lower edges of said lever apertures and, as the shelf reaches the horizontal position, the notches 64 provide for engagement of the levers with the lever apertures, the levers dropping slightly, or rotating clockwise, to provide for locking engagement of the notches 64 with said aperture edges, thus causing a slight upward movement of the integral trigger portions 60 of the lever to extend these portions through slots 62 to such a degree that manual depression of the trigger portions 60 will release the notches 64 from locking relation with the lever aperture edges. The shelf 38 is thus locked in horizontal position by the levers 50 which serve as the reaction or thrust members for the shelf and objects which may be placed thereon. The detents 66 serving to define in part the notches 64 serve as catch members to prevent disengagement of the levers 50 from the lever apertures 56, thus serving to also prevent a raising of the shelf 38 beyond the slight degree above the horizontal level afforded by the particular width of the notches 64.

The levers 50 are each provided with a cam spur or lobe portion 59 at the rearward end of the arcuate lever portion 54. These cam spurs 59 in conjunction with bevelled upper edges 61 of the apertures 56 constitute means for positively forcing the levers downwardly so that the slots 64 thereof are brought into locking relation with the lower edges of the apertures 56, whereupon the detents 66 prevent full withdrawal of the levers from the apertures. The transverse dimension of the rearward ends of the levers, i. e., from the tip of the cam spurs 59 to the tip of the detents 66, is greater than the vertical dimension of the locking apertures. Thus, if the levers were to become accidentally frozen in their normal guided position with respect to the apertures, as indicated in dotted outline in Figure 7, the cam spurs 59, in coming into engagement with the bevelled edges 61 of the apertures, will positively cam the levers downwardly to cause the lower edges of apertures 56 to reside within the elongated notches 64. If the shelf is raised slightly above the horizontal position, the detents 66 serve as stop members, and, when the shelf gravitates to the horizontal position, the forward ends of the notches 64 come into abutting, or locking, relation with the molding strips 28, as shown in solid outline in Figure 7. Thus, the forced camming of the levers under the action of cam spurs

59 positively positions the levers for two-way locking action with the molding strips 28.

To disable the locking means and restore the shelf 38 to its folded or collapsed position, the operator merely simultaneously depresses the trigger portions 60 of the levers 50 to impart the required degree of counter-clockwise rotation of the levers to free the notches 64 from locking engagement with the lever apertures, followed by a manual lowering of the shelf to its vertical position. During the lowering operation of the shelf the arcuate portions 54 of the levers travel inwardly of the splash-plate member 10 about the centers of rotation constituted by the pivot members 48.

Means are also embodied in the shelf mechanism to render the molding strips 28 adjustably positionable with respect to the pivotal axis of the shelf, to thereby ensure that the shelf in its raised locked position will be truly horizontal. The preferred embodiment of this means for adjustment involves the clamping together of the brackets 22 and the molding strips 28 in adjustable relation on the wall 12 of the splash-plate member 10 in such fashion that the strips 28 are vertically adjustable with respect to the brackets 22, and, therefore, to the links 32, said adjustment means comprising elongated slots 68 in the brackets 22, elongated slots 58 and 70 in the wall 12, and elongated slots 72 in the strips 28. The lower bolts 24 extend through slots 68 and 70, while the upper bolts 24 extend through slots 58 and 68. The links 32 extend through the slots 72 of strips 28. If it is desired that the positional relation between the lower or locking edge of apertures 56 and the pivots 48 be adjusted so that the upper surface of the shelf in its locked position will be within a true horizontal plane, this may be done by loosening the bolts 24, varying the vertical position of the bolts in bracket slots 68 to the necessary degree, and re-tightening the bolts.

It will be noted that the splash-plate 10 is shown as being provided with a light or lamp member 68 adapted for the conventional purposes, said light being covered and partially enclosed by the shelf 38 when the latter is in its vertical position.

From the foregoing description of the preferred structural embodiment of the shelf mechanism, it will be clear that I have provided a readily and efficiently operable collapsible shelf structure well adapted for the attainment of the objects of the invention hereinabove set forth. Since it will be obvious to those skilled in the art to which this invention pertains that certain changes and modifications may be made in the structure without departing from the spirit of the invention, it is intended that the scope of the invention be defined by the scope of the appended claims.

What I claim as new and desire to secure by Letters Patent is:

1. A device of the class described comprising a support member, a shelf pivotally supported therefrom and movable from a dependent vertical position to a horizontal position for use, an escutcheon plate member carried by said support member, an unbalanced first class lever having a pivotal connection with said shelf and having at its overbalanced end an arcuate portion offset in a direction away from said shelf, said arcuate portion of said lever being adapted to travel within a slot formed in said escutcheon member, said slot being located at a lower level than the 70 pivotal axis of said shelf, a notch in the under-

side of said arcuate portion operable upon the movement of said shelf to its horizontal position to engage with the lower edge of said slot to secure said shelf in said position, said lever being releasable from locking engagement with said slot to enable downward movement of said shelf upon the application of a downward force to the underbalanced end of said lever sufficient to reversely overbalance said lever, and means forming an adjustable connection between said escutcheon member and said support member enabling a variable positioning of said slot with respect to the pivotal axis of said shelf to thereby selectively vary within limits the locking position plane of said shelf.

2. A device of the class described comprising a fixed support member, a shelf, a pair of outrigger lever housings fixedly attached to the sides of said shelf and parallel therewith, pivotal connections between the rearward ends of said housings and said fixed support member whereby said shelf is rendered pivotally movable from a dependent vertical position adjacent said support member to a horizontal position normal to said member, a first class lever residing in each housing and having a pivotal connection therewith, said levers being overbalanced at their rearward ends and having arcuate portions at said ends offset downwardly and rearwardly with respect to said shelf, when said shelf is in its horizontal position, and slidably within slots formed in said support member in pressing engagement, due to the overbalancing of said levers, with the lower edges of said slots, a slot in the top side of each of the forward ends of said outrigger housings, an upstanding lug on each of said levers at the forward or underbalanced ends thereof extending through said housing slots, and a notch in the underside of the arcuate portion of each lever adapted to engage the lower edges of the support member slots to lock the shelf in a horizontal position, said shelf being releasable for downward movement by pressure applied downwardly to said lugs to reversely overbalance said levers to disengage said notches from said slot edges.

3. A device of the class described comprising a fixed support member, a shelf pivotally connected thereto and movable from a dependent vertical position to a horizontal position for use, an unbalanced first class lever having a pivotal connection with said shelf and having at its overbalanced end an arcuate portion offset in a direction away from said shelf, said arcuate portion of said lever extending through a slot formed in said support member, said slot being located at a lower level than the pivotal connection between said shelf and support member, a notch in the underside of said arcuate portion operable upon the movement of said shelf to its horizontal position to engage with the lower edge of said slot to secure said shelf in said position, an enlarged camming portion at the upper side of the rearward end of the arcuate portion of said lever engageable during movement of the shelf to its horizontal position with the upper edge of said slot to positively engage said notch with the lower edge of said slot to prevent accidental full withdrawal of said lever from said slot, said notch being relatively elongated and so positioned with respect to the camming portion of the lever that upon engagement of the camming portion with the upper edge of the slot to bring the notch onto said slot edge said shelf may

be moved to a position slightly above the horizontal, the rearward side of said notch being operative as a stop member in engagement with the support member to prevent further raising of the shelf, the forward side of said notch then being operative upon the return of said shelf to horizontal position to engage said support member and prevent further lowering of the shelf, said lever being releasable from locking engagement with said slot to enable downward movement of the shelf upon the application of a downward force to the underbalanced end of said lever sufficient to reversely overbalance said lever.

4. A device of the class described comprising a fixed support member, a shelf pivotally connected thereto and movable from a dependent vertical position to a horizontal position for use, an unbalanced lever having: a pivotal connection with said shelf located between the ends of the lever; an underbalanced forward end having a portion thereof extending above the level of the upper surface of said shelf; and an overbalanced rearward end in sliding engagement with said support member; said lever having at its overbalanced rearward end an arcuate portion offset in a direction away from said shelf, said arcuate portion of said lever being adapted to travel within a slot formed in said support member, said slot being located at a lower level than the pivotal connection between said shelf and support member, a notch in the underside of said arcuate portion operable upon the movement of said shelf to its horizontal position to engage with the lower edge of said slot to secure said shelf in said position, said lever being releasable from locking engagement with said slot to enable downward movement of said shelf upon the application of a downward force to the underbalanced end of said lever constituted by the portion thereof extending above the upper surface of said shelf sufficient to reversely overbalance said lever, said lever being provided with an enlarged cam lobe at the upper side of the rearward end of the arcuate portion thereof, said cam lobe being engageable with the upper edge of said slot during movement of the shelf to its horizontal position to positively engage said notch with the upper edge of said slot to prevent accidental full withdrawal of said lever from said slot.
